UNITED STATES PATENT OFFICE.

RALPH R. ROOT, OF CLEVELAND, OHIO.

ELECTRIC SIGNALING DEVICE.

1,328,454.

Specification of Letters Patent. Patented Jan. 20, 1920.

Application filed February 8, 1915. Serial No. 6,683.

To all whom it may concern:

Be it known that I, RALPH R. Root, a citizen of the United States, residing at Cleveland, in the county of Cuyahoga and State of Ohio, have invented a certain new and useful Improvement in Electric Signaling Devices, of which the following is a full, clear, and exact description.

This invention relates to a signaling device of the type which is generally known as electric horns. The particular horn herein shown and described is of the vibrator type and is an improvement upon the horn disclosed in my application, Serial No. 815,343, filed January 30, 1914, Patent No. 1,160,766, issued Nov. 16, 1915.

The object of the invention is to improve the construction of an electric vibrator horn, simplifying the construction and enabling the horn to be produced at low manufacturing cost.

Generally speaking, the invention comprises the elements and combinations thereof set forth in the accompanying claims.

Reference should be had to the accompanying drawings forming a part of this specification, in which Figure 1 is an elevation with parts in section of the horn of my invention; Fig. 2 is a rear elevation of the horn with the casing surrounding the working parts in section; and Fig. 3 is an enlarged section of the condenser shown in Fig. 1.

In the drawing at 1 there is shown what I term a base, the same being a saucer-shaped element having an opening at substantially the central portion thereof. With this opening there co-operates an amplifier generally represented at 2.

The base 1 is formed with a shoulder 2', which extends entirely around the base, and upon this shoulder rests a diaphragm 3. This diaphragm is made of flexible material. A support 4 having an offset flange 5, has the flange portion thereof resting against the diaphragm 3 and the flanged portion extends outwardly so as to lie above the shoulder 2' of the base 1. The base 1 has an extending portion 6 which is adapted to be folded around the edge of both the diaphragm 3 and the flange of the support 4 so that the base 1, the diaphragm 3 and the flange 5 are all held together as a unitary structure.

At the central portion of the support 4 there is an opening through which extends

a head 7 carried by a central core 8. This core has an opening through the central portion thereof, and through the opening there extends a post 9. This post at one end is unsecured, and its opposite end is fastened in any desired manner to substantially the central portion of the diaphragm 3.

Resting upon the support 4, and surrounding the core 8 is a cup-shaped member 10. This cup-shaped member is provided with a central opening through which extends the head 7 of the core 8. The portion of the head 7 which extends beyond the support 4 is upset so that the core 8 and the cup-shaped member 10 are securely held upon the support 4.

The cup-shaped member 10 has an extension 11 which is bent so as to raise the level of the extension above the top of the cup 10. This extension and the upper portion of the cup are provided with a downwardly extending flange 11' for the purpose of stiffening the construction.

The extension 11 is formed integral with the cup 10 so that by a stamping operation the cup and its extension may be formed.

The extension 11 supports an armature 12 and the make and break members which will be presently described.

The armature 12 is supported upon a spring plate 13, the end of this plate resting upon the extension 11. Above the plate 13 is a spring 14 which carries one of the contacts 15. This spring extends to substantially the central portion of the armature 12, and the end of the spring 15 passes beneath a transversely extending retaining member 16. As the armature moves, the retaining member will act to positively move the spring member 15 and thus positively operate the make and break device. The spring 14 is insulated from the spring 13, as indicated at 17.

Above the spring 14 is a second spring member 18, which carries a contact 19 which co-operates with contact 15. The spring member 18 is insulated from the spring member 14, as indicated at 20. The spring member 18 is formed with a side extension 18^a, indicated at 18^a, and the spring member 14 is formed with a side extension member indicated at 14^a, these extensions being for the purpose of receiving wires forming part of the electric circuit for the horn.

The members 13, 14, 18, and the insulating members which separate them are all

provided with suitable openings through which extend screw bolts 21. These screw bolts extend through openings formed in the extension 11, and thus secure the various 5 elements recited to the extension 11. The openings in the members 13, 14 and 18 through which the bolts 21 extend are made sufficiently large so that the shanks of the bolts do not touch the plates while the openings 10 in the insulating members are made of proper size to just fit the shanks of the bolts. These precautions prevent short-circuiting.

The post 9 which has heretofore been described, extends slightly beyond the core 8, but the end thereof is spaced a slight distance from the armature 12. In operation the attraction of the armature causes the armature to strike a blow against the post 9, 15 which blow is transmitted to the diaphragm 3, causing the diaphragm 3 to vibrate and produce a sound which continues as long as a succession of blows is imparted to the post 9 by the armature 12.

20 Within the cup 10 is a coil 22, which surrounds the core 8. This coil is of usual construction, and requires no description. The coil is held in the cup 10 by means of a top plate 23 which is secured in any desired manner.

25 A yoke 24 is carried by the support 4 to which it is secured. This yoke extends above and across the electro-magnet and armature. The yoke is provided with two screws 25 and 25^a which receive the conductors from the battery.

30 One of the conductors coming from the battery will be secured to the screw 25, while the other conductor will be secured to the 40 screw 25^a.

35 There is a conductor 26 extending from the screw 25 which enters an opening 10^a in the cup 10. This conductor is secured to one of the terminals of the coil 22, while the other terminal of the coil is connected 45 with a conductor 27 which may be secured to the extension 14^a upon the plate 14. Another conductor 28 may be utilized to connect the extension 18^a of the plate 18 50 with the screw 25^a.

The screw bolt 25 is insulated from the conductors coöperating with the lower portion of the element 24.

55 The operation of the horn is as follows: With the parts in the position shown in the drawing, and the electric current supplied to the entering conductors, current will flow between the contacts 14 and 15 and through the coil 22. This will cause the armature 60 12 to be attracted toward the cup 12 and impart a blow to the post 9. The movement of the armature will break the electrical connection between the contacts 14 and 15, which will cause the demagnetization of the 65 electromagnet formed by the cup 10 and

the coil 22 therein, and the armature 12 will return to the position shown in the drawing, under the action of the springs 13 and 14.

The features of construction to which attention is especially called is the fact that 70 the cup 10 and the support for the spring which in turn supports the armature, also the support for the make and break device, is an integral structure and may be formed at a single stamping. This makes it possible 75 to construct an efficient horn at a very low cost of manufacture.

A cover 40 incloses all the operating elements of the horn. It is provided with a flange around the lower portion thereof 80 which engages the support 4 and against the shoulder formed in this support by the offset flange 5. The cover 40 is held to the yoke 24 by a screw 41.

In horns of the type herein disclosed there 85 is apt to be trouble due to sparking between the contact points of the make and break device.

It is possible to substantially eliminate this spark by providing a separate path for 90 the current which would be flowing between the contacts at the time of break. The current induced in the coil by the breaking of the circuit is caused to pass into a condenser which is represented at 29. The terminals 95 of the condenser, 30 and 31, are secured in parallel with the contact points 14, 15, the connectors 30, 31, being connected with the portions 18^a and 14^a. The condenser 29 is made up of strips of tin foil which are 100 alternately arranged, with intermediate strips of insulating material, that is to say, ordinary and usual condenser construction.

The projecting portions of the tin foil upon each side of the condenser are pressed 105 against brass rings 32 and 33. To the brass ring 32 is connected the connector 30, and to brass ring 33 the connector 31 may be connected.

These elements when assembled are 110 wrapped in material which securely envelops the tin foil and rings as indicated at 34, and a casing formed from two telescoping parts 35 and 36, envelops the whole. The form thus imparted to the condenser 115 is that of a hollow ring, and the interior diameter of the casing is such as to snugly fit over the cup 10. The fit may be sufficiently snug so that it will require no additional means for holding the condenser in 120 place on the cup 10 than the friction of the engagement.

It will be seen that at the time of the parting of contacts 14 and 15 the current then flowing will find a path into the condenser and there be absorbed.

Having described my invention, I claim:

1. In an electric signaling device, the combination with a supporting means, of a diaphragm carried by the supporting means, 130

- an electromagnet, an armature for the electromagnet, means for communicating the movement of the armature to the diaphragm, a resilient member supporting the 5 armature, means for supporting the resilient member, a pair of contact members supported adjacent the armature, but independently of the armature and extending over the same, a cross member supported 10 by the armature which cross member normally overlies one of the contact members, the said cross member slidably engaging and moving one of said contact members when the armature is attracted.
- 15 2. In a signaling device, the combination of a supporting means, a diaphragm carried by the supporting means, an electromagnet carried by the supporting means, an armature, means for transmitting the vibration 20 of the armature to the diaphragm, a make and break device, a yoke carried by the sup-

porting means, a cover incasing the operating parts of the device said cover being secured to the yoke.

3. In a signaling device, the combination 25 of a support having an offset portion, a diaphragm secured to the support, an electromagnet carried by the support, an armature, means for transmitting the vibration of the armature to the diaphragm, a make and 30 break device, a yoke carried by the support, a cover resting against the support and engaging the shoulder of the offset portion and means for securing the cover to the yoke.

35 In testimony whereof, I hereunto affix my signature in the presence of two witnesses.

RALPH R. ROOT.
